The ornamental design for a left front fender for a vehicle, as shown and described.

DESCRIPTION

FIG. 1 is a front-right perspective view of the left front fender for a vehicle, showing my new design;

FIG. 2 is a front-left perspective view thereof;

FIG. 3 is a right side view thereof;

FIG. 4 is a left side view thereof;

FIG. 5 is a top view thereof;

FIG. 6 is a bottom view thereof;

FIG. 7 is a front view thereof; and,

FIG. 8 is a rear view thereof.

The broken lines shown in the drawings illustrate portions of the left front fender for a vehicle that forms no part of the claimed design.
